US0D1044044S

(12) **United States Design Patent** (10) Patent No.: **US D1,044,044 S**
(45) Date of Patent: ** Sep. 24, 2024

(54) **ROOFING MATERIAL**

(71) Applicant: **BMIC LLC**, Dallas, TX (US)

(72) Inventors: **Kevin Peter McGrath**, Denville, NJ (US); **Soufiane Mohand Kaci**, Lincoln Park, NJ (US); **Eric R. Anderson**, Montclair, NJ (US)

(73) Assignee: **BMIC LLC**, Dallas, TX (US)

(***) Term: **15 Years**

(21) Appl. No.: **29/924,520**

(22) Filed: **Jan. 19, 2024**

(51) LOC (14) Cl. **25-01**

(52) U.S. Cl.

USPC **D25/139**

(57) **CLAIM**

The ornamental design for a roofing material, as shown and described.

DESCRIPTION

FIG. 1 is a top perspective view of an embodiment of a roofing material;

FIG. 2 is a front view of the embodiment shown in FIG. 1; FIG. 3 is a rear view of the embodiment shown in FIG. 1; FIG. 4 is a left side view of the embodiment shown in FIG. 1;

FIG. 5 is a right side view of the embodiment shown in FIG. 1;

FIG. 6 is a top view of the embodiment shown in FIG. 1; and,

FIG. 7 is a bottom view of the embodiment shown in FIG. 1.

The broken lines illustrate portions of the roofing material that form no part of the claimed design. The dashed break-away lines also form no part of the claimed design.

The appearance of any portion of the roofing material between the break lines shown in FIGS. 1 and 3-7 form no part of the claimed design.

1 Claim, 7 Drawing Sheets
